UNITED STATES PATENT OFFICE.

ADOLF KRAUSS, OF CANNSTATT, GERMANY, ASSIGNOR, BY MESNE ASSIGNMENTS, TO
AMERICAN BOSCH MAGNETO CORPORATION, OF NEW YORK, N. Y., A CORPORATION
OF NEW YORK.

MECHANICAL INTERRUPTER FOR ELECTRIC IGNITION SYSTEMS.

1,337,456

Specification of Letters Patent. Patented Apr. 20, 1920.

Application filed February 28, 1918. Serial No. 219,735.

To all whom it may concern:

Be it known that I, ADOLF KRAUSS, a subject of the German Emperor, residing at and whose post-office address is Cannstatt, 5 Bryestrasse 8, Germany, have invented certain new and useful Improvements in Mechanical Interrupters for Electric Ignition Systems; and I do hereby declare the following to be a full, clear, and exact description of the invention, such as will enable others skilled in the art to which it appertains to make and use the same.

The present invention relates to mechanical interrupters for electric ignition systems intended to be associated with internal combustion engines, and more particularly to a deflectable interrupter lever having a supporting structure comprising a spring attached to the lever and supported in such 20 manner as to reduce the possibility of breakage and loosening.

As is well known to those skilled in the art, the leaf spring employed in a certain type of mechanical interrupter for supporting the deflectable lever from the bearing member, is liable to break rather easily; moreover, the means of fastening the spring to the bearing member is not free from objections. In those cases in which the spring 30 is fastened at a place intermediate its ends to the bearing member by means of a screw, the hole through which the screw passes is apt to weaken the spring precisely where it undergoes the most severe stress, the edges 35 of the bearing member limiting the movement of the spring on both sides of the place of its connection.

In accordance with the present invention, the foregoing objections are eliminated by 40 supporting the spring intermediate its ends at two separated places, to form a free spring section therebetween. In the specific embodiments hereinafter disclosed, the spring is clamped between the bearing member and a clamping member gripping the 45 spring between them at the two separated places which may be constituted by comparatively sharp edges or by opposed faces having comparatively extended areas. In 50 this way, the part of the spring intermediate the edges or the extended areas is free from any substantial bending stress so that the possibility of breaking is almost completely averted. If desired, the bearing

member and the clamping member may be 55 fastened by a screw passing through the free spring section without weakening the spring in a part subjected to material bending stress.

In the drawings affixed to this specification and forming a part thereof, the interrupter elements are, as an example, carried by an interrupter disk intended to rotate with the armature of a magneto for periodic coöperation with normally stationary cams. 65 In these drawings, Figures 1, 3 and 5 are front views of three modifications within the invention; and Figs. 2, 4 and 6 are axial views of portions thereof.

In Figs. 1 to 6, the rotatable interrupter 70 disk *a* carries, in a well known manner, the contact *b* of the block *c*, and also has fastened to it in any suitable manner a bearing member *e*. The deflectable lever *f* carrying at one end a block adapted to periodically engage the interrupter cams and at the other end an interrupter contact coöoperative with the contact *b*, has affixed near its ends the two ends of a supporting spring *g* or magazine of springs of any suitable kind. 80 That spring is clamped intermediate of its ends between the bearing member *e* and a clamping member *h*, which grip the spring at two places *i* and *k* separated from each other to form a free spring section therebetween substantially free from any material bending stress.

In the modification of Figs. 1 and 2, the bearing member *e* has two separated upstanding portions, whereas the clamping 90 member *h* is in the form of an eccentric, conical or other suitable form of pin arranged, when positioned, to grip the spring *g* between it and said upstanding portions at the points *i* and *k*.

In the modification of Figs. 3 and 4, the upstanding portion of the bearing member has a continuous surface, whereas the clamping member *h* is partly cut away to form two sharp edges adapted, when positioned, 100 to grip the spring *g* between it and the bearing member at the two separated places *i* and *k*.

In the embodiment of Figs. 5 and 6, the clamping member *h* has two flat surfaces 105 of extended area separated from each other, and adapted to clamp the spring *g* between them and the bearing member *e*, the inter-

mediate part of the clamping member being so shaped as to leave a free spring section therebetween, as shown. The screw *l* fastens the bearing and clamping member together, 5 and passes through the free section of the spring.

As a result of the fact that the spring *g* is gripped between the bearing and clamping members at two separated places to form 10 a free spring section therebetween, all practical danger of breakage or loosening of the spring is averted. Furthermore the bending efforts exerted on the spring are almost perfectly balanced.

15 Having thus described my invention, what I claim is:

1. In a mechanical interrupter for electric ignition systems, an interrupter lever, a deflectable interrupter lever coöperative therewith, a spring having its ends fastened to the deflectable lever, and clamping means gripping the spring intermediate its ends at two separated places to form a free spring section therebetween.

20 2. In a mechanical interrupter for electric ignition systems, an interrupter lever, a deflectable interrupter lever coöperative therewith, a spring having its ends fastened to the deflectable lever, a bearing member, and

25 30 a clamping member, the two members gripping the spring intermediate its ends at two separated places to form a free spring section therebetween.

35 40 3. In a mechanical interrupter for electric ignition systems, an interrupter lever, a deflectable interrupter lever coöperative therewith, a spring having its ends fastened to the deflectable lever, and bearing and clamping members gripping the spring intermediate its ends at two separated places to form a free spring section therebetween, one of

said members having a cut-away portion intermediate its gripping places.

4. In a mechanical interrupter for electric ignition systems, an interrupter lever, a deflectable interrupter lever coöperative therewith, a spring having its ends fastened to the deflectable lever, and bearing and clamping members gripping the spring intermediate its ends at two separated places to form 45 a free spring section therebetween, the clamping member having a cut-away portion intermediate its gripping places.

5. In a mechanical interrupter for electric ignition systems, an interrupter lever, a deflectable interrupter lever coöperative therewith, a spring having its ends fastened to the deflectable lever, and bearing and clamping members gripping the spring intermediate 50 its ends at two separated places to form a free spring section therebetween, the clamping member having two gripping surfaces of extended area with a cut away portion 55 intermediate its gripping places.

6. In a mechanical interrupter for electric ignition systems, an interrupter lever, a deflectable interrupter lever coöperative therewith, a spring having its ends fastened to the deflectable lever, bearing and clamping members gripping the spring intermediate 60 its ends at two separated places to form a free spring section therebetween, and a fastening device passing through the free section of the spring to secure the members together with the spring therebetween.

70 75 In testimony whereof I affix my signature in presence of two witnesses.
